(57) **CLAIM**

The ornamental design for a mitre connector assembly, as shown and described.

DESCRIPTION

FIG. 1 is a perspective view of the mitre connector assembly of the invention, in fully closed position;

FIG. 2 is a side elevational view of the mitre connector assembly, the opposite side elevational view being a mirror image thereof;

FIG. 3 is an end elevational plan view of the mitre connector assembly, the opposite end elevational view being a mirror image thereof;

FIG. 4 is a top plan view of the mitre connector assembly; and,

FIG. 5 is a bottom view of the mitre connector assembly.
